[57] CLAIM

The ornamental design for an electronic hand control
unit for adjustable bed, as shown and described.

DESCRIPTION

FIG. 1 is a front elevational view of an electronic hand
control unit for adjustable bed embodying my new
design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and

FIG. 7 is a perspective view thereof on an enlarged
scale.
